CLAIM

The ornamental design for a water bottle, as shown and described.

DESCRIPTION

FIG. 1 is a top plan view of a water bottle, showing our new design, shown without cap for ease of illustration.

FIG. 2 is a top cross-section view thereof, taken along line 2-2 in FIG. 3.

FIG. 3 is a front elevation view thereof, shown without cap for ease of illustration.

FIG. 4 is a front cross-section view thereof, taken along line 4-4 in FIG. 1.

FIG. 5 is a bottom plan view thereof.

FIG. 6 is a bottom cross-section thereof, taken along line 6-6 in FIG. 3.

FIG. 7 is a top plan view thereof, shown without the bottle for ease of illustration.

FIG. 8 is a front cross-section view thereof, taken along line 8-8 in FIG. 7.

FIG. 9 is a side cross-section view thereof, taken along line 9-9 in FIG. 7.

FIG. 10 is a bottom plan view thereof, shown without the cap for ease of illustration.

FIG. 11 is a side elevation view thereof, shown without the cap for ease of illustration; and,

FIG. 12 is a side cross-section view thereof, taken along line 12-12 in FIG. 1.
